UNITED STATES PATENT OFFICE.

STEPHEN C. HENDRICKSON, OF BROOKLYN, N. Y., ASSIGNOR TO THE UNION SWITCH AND SIGNAL COMPANY, OF PITTSBURG, PENNSYLVANIA.

ELECTRIC RAILWAY-SIGNAL.

SPECIFICATION forming part of Letters Patent No. 276,038, dated April 17, 1883.

Application filed May 13, 1882. (No model.)

To all whom it may concern:

Be it known that I, STEPHEN C. HENDRICKSON, a citizen of the United States, and a resident of Brooklyn, in the county of Kings and State of New York, have invented certain new and useful Improvements in Electric Railway-Signals, of which the following is a specification.

The object of my invention is to provide a series of semaphoric or visual signals placed at suitable intervals along the line of a railroad in such manner that a signal denoting "danger" will be automatically exhibited by the passage of each train, and will remain visible and in a position denoting that the track is obstructed until the train which actuated it has passed under the protection of the next succeeding signal of the series, when the first-mentioned danger-signal will be withdrawn or reversed, or otherwise made to indicate that the track is clear. By this means a train following another upon the same track may be cautioned, and thus prevented from approaching too closely to the preceding train, or coming in collision with it. This general system of signals is termed an "automatic block or space system."

My invention relates to apparatus and mechanism which is operated by electro-magnetism, and is employed in carrying out the above-described system.

The invention consists in certain improved methods of combining and arranging the circuit-closer, conductors, batteries, signals, and signal-operating mechanism, whereby greater efficiency and economy of operation are secured, and any accidental interruption or failure to operate on the part of the electrical portion of the apparatus will be instantly indicated.

The combinations of mechanism and apparatus which constitute the novel features of the invention will be hereinafter particularly described, and pointed out in the claims at the end of this specification.

In the accompanying drawings, which represent the best means of carrying out my invention now known to me, Figure 1 is a view in elevation of the visual signal and signal-actuating mechanism. Fig. 2 is an elevation, on a reduced scale, of the case or box within which

the signal is placed. Fig. 3 is a diagram illustrating the various positions assumed by the signal-disk; and Fig. 4 is a theoretical diagram illustrating the arrangement of the electric circuits in connection with the railroad-track, whereby all signals are actuated in connection with the moving of the trains along said track. 55

Referring to Fig. 1, D represents the signal-disk, which may conveniently be made thirty or forty inches in diameter, more or less, and is preferably constructed of some thin and light material. The signal-disk is divided into four equal segments of alternately-contrasting colors—such, for example, as white and red, or white and black—one color, when exhibited, indicating "safety" and the other color "danger." For the purposes of this description the white segments d d are assumed to indicate "safety," and the shaded segments d' d' are assumed to indicate "danger." The disk D is caused to rotate, when required, in the direction indicated by the arrow, by means of a weight attached to the cord e, which is wound upon the drum C. This is mounted upon the axis of a toothed wheel, C', which engages with a pinion upon the shaft D', upon which the signal-disk D is mounted. The weight may be wound up, when required, by applying a key to the end of the arbor K. 75

Upon the main signal-shaft D' is fixed a scape-wheel, F, having eight teeth situated alternately in two planes. The scape-wheel is held in check by an oscillating anchor, B', of well-known construction, which permits one tooth of the scape-wheel to pass at each vibration, whether forward or backward. 80

Upon the frame A, which supports the signal-disk and its attached mechanism, is also mounted an electro-magnet, M, the armature of which is attached to a pivoted lever, B, having a fork at its upper end, which acts upon the downwardly-projecting arm b of the anchor B'. The pivoted armature-lever B is provided with an adjustable retractor, m, of the usual construction. Thus it will be understood that the disk D tends to revolve in the direction indicated by the arrow, whenever permitted to do so by the action of the escape-mechanism under the control of the electro-magnet M. 90

The apparatus is represented in Fig. 1 in

its normal position, in which a tooth of the escape-wheel F is held by the pallet b', and the armature of the electro-magnet M is drawn toward its poles by the action of a constant current traversing its helices. When the current through the electro-magnet M is interrupted its armature is drawn back by the retractor m and the forked end of the armature-lever B strikes the downward-projecting arm b of the anchor B' with a sudden blow, withdrawing the pallet b' from the tooth of the escape-wheel, and permitting the latter, together with the signal-disk D, to turn through one-eighth of a complete revolution, after which the succeeding tooth is caught by the pallet b' on the opposite side. When the circuit is closed again and the electro-magnet M becomes active its armature is drawn suddenly forward, another tooth of the escape-wheel is released, and the latter, together with the signal-disk, advances another eighth part of a revolution.

The signal-disk and mechanism for controlling the same, which has been described, are designed to be placed within a box or case, G, (see Fig. 2,) which is mounted upon a post, G', and placed at the side of and near the railroad-track, at the proper point, and at any convenient height above the ground. The signals are exhibited through two circular openings, g g, which may be from twelve to twenty-four inches in diameter, covered with glass, and illuminated at night by a lamp fitted with a reflector, which is placed in the box. If preferred, the two circular openings may be placed one above the other in a vertical line, instead of horizontally, as shown in the figure. Thus it will be understood that when the signal-disk D is in the position shown in Fig. 1 a white signal will be exhibited through the openings g g in the signal-box G; but when turned through one-fourth of a complete revolution the shaded or colored portion of the signal-disk will appear within the openings.

The organization of electric circuits which I prefer to make use of in connection with the signal mechanism hereinbefore described is shown in Fig. 4. T represents a line of rail-road-track of the usual construction, the portion of said track represented being one signal section or "block." At each signal-station—that is to say, between the ends of two adjacent blocks—is placed a circuit-closer of suitable construction, adapted to be operated by a moving train. I prefer to employ a track circuit-closer constructed as follows: Two rails or short sections of rails opposite each signal-station are insulated from the remainder of the track by well-known devices. I have shown such insulated rail-sections at T' and T'', and also at T''' and T''. At each signal-station is placed a differential electro-magnet, as shown at R, having two equal but opposing coils, r r'. A battery, e, has one of its poles united by a wire, w, with one terminal of each coil of the differential helix. The other end

of coil r is connected by a wire, w', to the opposite pole of the battery e. The remaining terminal of the opposing coil r' is connected with the insulated rail-section T'' by means of a wire, w''. The other insulated rail-section, T'', is connected by a wire, w'', to the remaining pole of the battery e. The opposite line of rails of the track is continuous, as shown at T'', and need not be insulated. The arrangement of circuits at the other end of the signal section or block is precisely similar to that which has been described, the connections of the differential electro-magnet R' being made with the insulated rail-sections T''' and T'' in the same manner. A normally-closed electric circuit extends from one signal-station to the other, which is made up of a direct wire, l, and return-wire l', for all of which wires the earth 85 may be substituted, if preferable, in any case. This circuit passes through the relay-contacts or circuit-breakers u u' at the respective signal-stations, these being controlled by the differential electro-magnets R and R'. In the 90 closed circuit l l' is included the signal-operating electro-magnet M, by which the apparatus described in connection with Fig. 1 is actuated, as hereinbefore explained. When the apparatus is in its normal position and no train passing, the electric circuit is closed through one coil, r, only of each of the differential relays R and R', while the circuit of the opposing coil r' in each of said relays is interrupted at the insulated rail-sections T'' and T''', 95 and also at T''' and T''; hence the armature-levers or circuit-breakers u and u' are drawn down by the action of the coil r, and the circuit through the signal-operating magnet M is closed. A train going in the direction indicated by the arrow closes the circuit through the opposing coil r' of the differential relay R, for the reason that its wheels and axles form a connection from the insulated track-section T'' to the continuous rail T'', and thence back again from the continuous rail T'' to the insulated section T'''. When the circuit is thus closed it causes a current to pass through the coil r', which neutralizes the action of the constant current in the opposing coil r, and thus 115 releases the armature-lever or circuit-breaker u, which is drawn back by the spring v, breaking the normally-closed circuit of the signal-operating magnet M, and permitting the signal-disk controlled thereby to turn through one-eighth of a complete revolution, as hereinbefore explained. The last-named circuit remains thus broken until the train has passed beyond the circuit-closer T'' T''', when the current traversing the differential-relay coil r' is broken, and the coil r, being no longer opposed by its action, draws down the armature-lever u and restores the circuit l l', thus advancing the signal-disk through another eighth of its revolution, and changing its indication from "safety" to "danger." When the train in its progress reaches the insulated rail-sections T''' and T'', or other circuit-closer at the other end of the block, the same operation is repeated, the

circuit of the electro-magnet M being broken by the armature-lever w during the time occupied by the train in passing over the circuit-closer $T^3 T^4$, and by reason of this breaking and closing the signal-disk advances through another quarter of its revolution, thus restoring its indication to "safety." Thus it will be understood that the indications of the signal, whether for "danger" or for "safety," can only be exhibited when an electric current is traversing the electro-magnet M. So long as the circuit remains interrupted the signal-disk will be held at a point, half-way between the two regular indications, and the indication will appear part of one color and part of the other. The successive indications of the signal, as exhibited through the openings g in the signal-box, are represented in Fig. 3, in which the first shows the normal or "safety" indication; the second the indication while the train is passing the circuit-closer $T^1 T^2$; the third the indication of "danger" which remains while the train is passing through the signal section or block; the fourth the indication while it is passing the circuit-closer $T^3 T^4$, and the fifth the indication after it has passed beyond the block, signifying "safety," and showing that the block is clear between the two signal-stations.

The organization of circuits and apparatus which has been described is that which is best adapted for use upon the line of a double-track railroad, or where the trains upon the track always pass in the same direction. In order to adapt the apparatus for use in connection with a track upon which the trains run in both directions, the only modification which is necessary to be made is to place an additional signal at the opposite end of each signal section or block, which is actuated or controlled by an electro-magnet, M' , (shown in dotted outlines in Fig. 4,) which is placed in the same circuit with the electro-magnet M, hereinbefore referred to. In case a continuous chain of signals is to be extended along the line of the railroad, it is only necessary to make use of one differential relay, with its attached circuit-closer and circuit-breaker, at each signal-station, the conducting-wires being extended along each adjacent signal-section in the manner indicated by the dotted lines l^3 and l^4 in Fig. 4.

It will be observed that with the arrangement of circuits which has been described the breakage of an electric conductor or the failure of a battery at any point will cause the signal-disk to assume the position represented in the second and fourth positions, Fig. 3, thus indicating that the apparatus is out of order, in case it remains in that position any greater length of time than that required for a train to pass over the circuit-closer at the beginning or end of the signal-section.

It is not essential that the particular device hereinbefore described for closing a circuit by the action of a moving train should be employed in connection with the other ap-

paratus. Any circuit-closer which is so constructed as to close and break the circuit but once during the passage of a train over a given fixed point will serve the purpose, although the organization which I have described is considered preferable.

I claim as my invention—

1. The combination, substantially as hereinbefore set forth, of a differential electro-magnet having one of its coils included in a normally-closed and the other in a normally-open electric circuit, a battery or generator common to both said circuits, a circuit-closer actuated by a moving train for closing said normally-open circuit, and a signaling apparatus controlled by the armature of said differential electro-magnet.

2. The combination, substantially as hereinbefore set forth, of an electro-magnet, a battery, two detached insulated sections of a mechanically-continuous line of rails forming the respective terminals of a normally-open circuit, including said electro-magnet and battery, and an electrically-continuous line of rails extending parallel to both insulated sections of the first line.

3. The combination, substantially as hereinbefore set forth, of a revolving shaft, a disk mounted thereon for alternately exhibiting a danger and a safety signal, a scape-wheel attached to said shaft, an electro-magnet, armature, and retractor, and pallets actuated by said armature, which are placed in such relation to the scape-wheel and the revolving shaft that the armature must be moved away from and returned to the magnet in order to permit said shaft to revolve the proper distance to conceal one signal and display a reverse one.

4. The combination, substantially as hereinbefore set forth, of a normally-closed electric circuit extending the whole length of a signal section or block, a circuit-breaker in said circuit at each end of the signal-section, adapted to be actuated by a moving train, and one or more signal-operating electro-magnets included in said normally-closed circuit.

5. The combination, substantially as hereinbefore set forth, of a normally-closed electric circuit extending the whole length of a signal section or block, a circuit-breaker in said circuit at each end of the signal-section, adapted to be actuated by a moving train, one or more electro-magnets included in said normally-closed circuit, and a signaling apparatus under control of said electro-magnet or magnets, adapted to exhibit a danger and a safety signal in alternation, one of said signals only being exhibited at each successive completion of the circuit.

In testimony whereof I have hereunto subscribed my name this 8th day of May, A. D. 1882.

STEPHEN C. HENDRICKSON.
